DISTILLATION OF BUTANE CONTAINING
HIGH BOILING CONTAMINANTSGlenn W. Wilson, Jr., Goose Creek, Tex., assignor
to Standard Oil Development Company, a cor-
poration of Delaware

Application July 29, 1944, Serial No. 547,251

3 Claims. (Cl. 202—40)

1

The present invention is directed to a method for preparing a butane feed stock. More specifically, it is directed to the preparation of a normal butane feed stock suitable as a charging material in isomerization processes.

It is necessary for the composition of the feed stock prepared for isomerization reactions to be carefully controlled. The yield, rate of reaction and catalyst life in isomerization processes are adversely effected by the inclusion in the feed stock of contaminants having a higher boiling range than the desired paraffinic hydrocarbons. As a specific example, in the isomerization in the vapor phase of normal butane the inclusion of pentane and heavier components, such as seal oil, in the stock charged to the isomerization process is extremely detrimental to the life of the catalyst and in addition causes the formation of undesirable polymers. It is desirable that the feed sent to such a butane isomerization process contain no more than 2 per cent of isobutanes, less than .5 per cent of pentane and substantially no seal oil.

A usual way for preparing the feed stock for a butane isomerization unit is by charging to a distillation tower a composition including normal and isobutanes, as well as a small portion of pentanes and seal oil. In the distillation tower, the major portion of the isobutane is removed as overhead while a bottoms fraction is withdrawn as the fraction to be used as the feed to the isomerization unit. This bottoms fraction is contaminated by substantially all of the pentanes charged to the distillation tower and by the seal oil charged to the tower, as well as additional seal oil picked up from the pump circulating the reflux to the tower.

It is an object of the present invention to prepare a hydrocarbon stream suitable for use as the charging stock to an isomerization unit, comprising a major portion of normal butane and including substantially no pentanes and heavier hydrocarbons, such as seal oil.

Other objects and advantages of the present invention may be seen from a reading of the following description taken with the drawing in which the sole figure is in the form of a diagrammatic flow sheet.

A mixed feed is discharged by line 11 into distillation column 12. It will be understood that distillation column 12 may be a conventional bubble tower provided with a large number of trays to aid in the satisfactory separation of fractions having different boiling points. Vaporization takes place within the column and a vaporous

2

fraction is removed as overhead through line 13, is condensed in condenser 14 and is discharged from the condenser by line 15 into storage drum 16. The liquid accumulating in drum 16 may be withdrawn through line 17 and pump 18. It is desirable that the major portion of the condensate be returned to the tower to serve as reflux therein and this portion of the stream may be returned by means of pump 18 and line 19 to the top of the tower. A minor portion of the condensate may be removed either continuously or intermittently as product by outlet 20.

Heat from an external source may be conveniently supplied to the material undergoing rectification in tower 12 by means of reboiler 21. The reboiler shown is of the conventional type, having steam inlet 22 and steam outlet 23. It will be understood that the steam is passed through tubes, not shown, in the reboiler and supplies heat to the reboiler by indirect heat exchange. Reboiler 21 is provided with a partition 24 which is arranged to form a weir and liquid may be injected into a lower portion of the reboiler on one side of the weir by inlet lines 25 and 26 and may be discharged from the lower portion of the reboiler on the other side of the weir through line 27. Vapors may be returned from the reboiler to the distillation column via line 28.

It will be evident that the extraneous heat supplied to column 12 for refluxing is added thereto by the bottoms fraction flowing from the bottom of the tower through line 25 to the heating section of reboiler 21 where the major portion thereof is vaporized and the vapors are returned to the lower portion of column 12 via line 28. In addition to the stream supplied the reboiler from tower 12 by line 25, an extraneous feed is discharged into the heating section of the reboiler through line 26. The major portion of this stream is also vaporized in the reboiler with the vapors passing through line 28 into column 12.

It is desirable to supply more liquid to reboiler 21 than is vaporized therein so that a minor portion of the ingredients charged to the reboiler flow over the upper edge of weir 24 as a stream and is withdrawn continuously through line 27. The major portion of the stream withdrawn through line 27 will be normal butane. It is advantageous to discard this stream because of the substantial amounts of heavier hydrocarbons, such as pentanes and seal oil included therein. The desired fraction for the isomerization feed comprising a major portion of normal butanes with a very small amount of contaminants may

be withdrawn from the lower portion of tower 42 via line 28.

The following is given as an example of suitable operating conditions in the practice of the present invention with the composition of the stream fed into the system and the stream removed therefrom. In a tower containing 40 plates, a feed stream is discharged above the 24th plate at a temperature of 145° F. The volumes of components added per hour are shown in the following table:

Table I

	Gals./hour
IC4	4,980
NC4	10,002
IC5	18
Total	15,000
Seal oil, 30 lbs./day.	

Feed is added to reboiler 21 via line 26 as indicated in the following table:

Table II

	Gals./hour
IC4	80
NC4	3,912
IC5	5
Total	4,000
Seal oil, 100 lbs./day.	

The vapors are removed as overhead through line 13 at the rate of 78,000 gallons per hour and 72,000 gallons per hour are returned as reflux while the remainder, 6,000 gallons per hour, is withdrawn as product. The pump 18 used to return the reflux adds 200 pounds of seal oil per day to the reflux of the tower of which some 185 pounds are returned to the tower. The composition of that portion of the overhead withdrawn as product is as follows:

Table III

	Gals./hour
IC4	4,800
NC4	1,200
Total	6,000

Bottoms are withdrawn from the tower to the steam reboiler at the rate of 89,000 gallons per hour while vapors are returned from the reboiler to the column at the rate of 90,000 gallons per hour. Bottoms withdrawn from reboiler 21 via line 21 at the rate of 3,000 gallons per hour have the following composition:

Table IV

	Gals./hour
IC4	50
NC4	2,941
IC5	9
Total	3,000
Seal oil, 293 lbs./day.	

The hydrocarbon stream withdrawn via line 28 as the feed for a butane isomerization unit at the rate of 10,000 gallons per hour, has the following composition:

Table V

	Gals./hour
IC4	210
NC4	9,773
IC5	17
Total	10,000
Seal oil, 22 lbs./day.	

With this procedure the top of the tower is maintained at a temperature of 135° F., the bottom of the tower at a temperature of 164° F. and the condensate accumulating in drum 18 has a temperature of 128° F.

It will be seen that the stream removed by line 29 has present therein approximately 2 per cent of isobutane and negligible amounts of isopentanes and heavier hydrocarbons, such as seal oil, 10 and is a satisfactory feed stock for use in the 15 isomerization of normal butane. It will be understood that the above example is given only by way of illustration and not by way of limitation. It will be evident to the skilled worker that the 20 rate of operation, the composition of the streams and the temperatures employed may be varied over a substantial range without departing from the scope of the invention.

Having fully described the present invention, 25 what I desire to claim is:

1. A continuous method for distilling a primary feed mixture including at least a first component, a higher boiling second component, and a contaminating amount of a component boiling substantially higher than said second component comprising the steps of continuously introducing a stream of said primary feed mixture into a medial portion of a fractional distillation column, maintaining the distillation column under temperature and pressure conditions to cause removal of predominantly said first component substantially free of the contaminating component as a vapor from the top of column, continuously condensing said vapor to form a condensate, continuously returning at least a portion of said condensate as reflux to an upper part of said column while recovering another portion as distillate product, continuously removing from the bottom of the column a first and a second liquid stream, 30 said first stream being of greater volume than the second and each stream comprising predominantly said second component regulating the relative quantities of said first and second streams so that said second stream contains less than 35 10% by weight of the total high boiling components in the system, continuously recovering said second stream as liquid product, continuously introducing said first stream into a heated evaporation zone, supplementing the quantity of second component producible from said primary feed mixture by continuously introducing into the evaporation zone a second feed stream from a source external to said distillation column and 40 different from said primary feed mixture, said second feed comprising predominantly said second component and contaminating amounts of higher boiling components substantially in excess of the amount in said second stream, continuously vaporizing a major portion of the second component in the evaporation zone, continuously returning the resultant vapors to a section of the distillation column above the point of withdrawal of said first liquid stream but below said medial portion, and continuously removing from the evaporation zone a liquid stream including approximately 90% by weight of the total high boiling contaminants introduced into the distillation column and the evaporation zone.
2. A continuous method for obtaining a hydrocarbon fraction comprising a major portion of normal butane substantially free from higher boiling hydrocarbons comprising the steps of continuously charging a primary feed mixture including normal butane, isobutane and a minor

portion of higher boiling impurities to a medial portion of a distillation column, continuously maintaining the distillation column under temperature and pressure conditions to cause removal of a major portion of the isobutane charged to the column as overhead in vapor form, continuously condensing said vapor, continuously increasing the pressure on the resultant condensate and adding substantial amounts of higher boiling impurities thereto while increasing the pressure thereof, continuously removing a small portion of the condensate as product and returning a major portion of the contaminated condensate to the distillation column as reflux, continuously removing from the bottom of the column a first and a second liquid stream, said first stream being of greater volume than the second and each stream comprising predominantly normal butane, regulating the relative quantities of said first and second streams so that said second stream contains less than 10% by weight of the total high boiling components in the system continuously introducing said first liquid stream into an evaporation zone, supplementing the quantity of normal butane producible from the primary feed mixture by continuously introducing into the evaporation zone a second feed stream derived from a source other than said distillation column and the primary feed mixture, said second feed stream comprising predominantly normal butane contaminated with high boiling impurities substantially in excess of the amount in said second stream, continuously vaporizing a major portion of the normal butane in the evaporation zone and returning the resultant vapors to a lower

portion of the column, continuously recovering from the bottom of the distillation column said second stream comprising a major portion of normal butane substantially free from higher boiling impurities and suitable as feed for an isomerization step, and continuously withdrawing from the evaporation zone a liquid stream comprising substantial amounts of normal butane and approximately 90% by weight of the higher boiling impurities added to the distillation column and to the evaporation zone.

3. A method in accordance with claim 2 in which the upper portion of the distillation column is maintained at a temperature of the order of 135° F., the lower portion of the distillation column is maintained at a temperature of the order of 164° F. and in which the contaminants higher boiling than normal butane are present in the withdrawn bottoms fraction and in which the mixture is charged to the distillation zone at the rate of 15,000 gallons per hour, the fraction is added to the evaporation zone at the rate of 4,000 gallons per hour and in which the bottoms fraction is withdrawn as a product at the rate of 10,000 gallons per hour.
